**MEANS FOR CONTROLLING THE STROKE OF
FRICTION ON RODS IN FLAT KNITTING
MACHINES**

Fritz Flämig and Werner Koblitz, Ingolstadt, Germany, assignors to Schubert & Salzer Maschinenfabrik Aktiengesellschaft Ingolstadt, Ingolstadt (Danube), Germany

Application May 20, 1955, Serial No. 509,922

Claims priority, application Germany June 16, 1954

7 Claims. (Cl. 66—126)

This invention relates to new and useful improvements in controlling the stroke of friction rods in flat knitting machines. The invention more particularly relates to a control mechanism for controlling the stroke of friction rods in flat or full-fashion hosiery knitting machines during slow heel operation in connection with which the driving mechanism for the friction rods is coupled with the coulier mechanism which drives the slur bar.

In flat knitting machines the rotary motion of the driving motor is converted to a uniform reciprocal motion for driving the friction rods and the slur bar by means of the known coulier mechanism. This motion is known as the coulier motion. The friction rod carries the friction box with the thread guide for feeding the yarn to the needles, the width of travel of which is controlled by adjustable stops.

In the conventionally known arrangements for slow heel operation, the friction rod was actuated by a lever which was connected with the coulier mechanism by means of a connecting rod. The pivot point of the lever and the point of attachment with the connecting rod was suitably chosen with respect to the desired reduction of speed. In order to be able to vary the speed of the friction rod, the hole for connecting the connecting rod to the lever for slow heel operation was developed in the form of an elongated hole, allowing adjustment, or some other connecting mechanism was provided to allow this adjustment. The adjustment, however, had to be effected by hand and was time-consuming and cumbersome.

In another known device, a rack and gearing were provided, which were connected with the slur bar and actuated by it. In this device it was possible to reduce the speed of the friction rods which operated in rapid operation with the speed of the slur bar. The speed reduction, however, could only be effected to one of two reduced speeds, which corresponded to the approximate stocking width at the time. This device, however, was very limited in its range of action, since with the two speed steps it was possible to work with the slower movement of the friction rods only in the smallest and largest stocking widths of, for example, 8 and 13". In the intermediate range from, for example, 8 to 13", no change of speed of the friction rods was possible, so that the pressure on the stops provided to limit the motion of the friction rod was increased in a highly undesirable manner.

One object of this invention is a device of reducing the speed of the friction rods in a flat knitting machine without the above-mentioned disadvantages. This, and still further objects will become apparent from the following description, read in conjunction with the drawings, in which:

Fig. 1 is a plan view of an embodiment of a device in accordance with the invention shown in one operating position;

Fig. 2 is a plan view of the device shown in Fig. 1 shown in another operating position;

2

Fig. 3 is a side elevation partially in section of the device shown in Fig. 1; and

Fig. 4 is a plan view of a portion of a different embodiment of the device in accordance with the invention.

5 The invention is applicable to a flat knitting machine having a reciprocating member for driving the friction rod in slow heel operation, such as a drive bar which is imparted the coulier motion, i. e., a coulier bar; the reciprocating member, such as the bar, and the friction rod being movable along substantially parallel spaced-apart axes.

In accordance with the invention, a pivotal lever is used to transmit the reciprocating motion from the reciprocating bar to the friction rod and the pivot point of attachment 15 of the lever to the bar and to the member connected to the friction rod is changed along with the position of the lever's fulcrum point on the machine frame.

The lever may be pivotally connected at one end to its fulcrum, i. e., a pivot point connected to the machine frame, and at the other end to the friction rod, as, for example, through the driving slide for the friction rod.

20 The intermediate portion of the rod is connected to the reciprocating bar by a pivotal connection. The pivotal connection between the lever and one of the reciprocating 25 bar and friction rod can be axially slidable along the lever, and the pivotal connection between the other of the reciprocating bar and friction rod being slidably axially with the lever. The fulcrum point and the pivot points of the lever may be changed by providing means 30 for adjusting the fulcrum, i. e., the pivot point by moving the same substantially normal to the axes of movement of the friction rod and the reciprocating bar. These latter means may, for example, consist of a threaded spindle rotatably secured to the knitting machine frame 35 and an internally threaded sleeve member in threaded engagement to the spindle to which the pivot, i. e., the fulcrum of the lever is attached.

The movement of the fixed pivot point, as, for example, by rotating the threaded spindle, may be effected 40 with the conventionally known control devices, as, for example, by means of the control of the stops for the friction box which control the width of the goods being knit.

The device in accordance with the invention makes it 45 possible to adapt the speed of the friction rods within the normal range of width of, for example, 8 to 13", corresponding to the variable width of the reinforcement part of the stocking being knit. The invention will be described in further detail with reference to the embodiments shown in the drawing.

Referring to the embodiment shown in Figs. 1 to 3 of the drawing, 2 is a reciprocating drive bar, i. e., the coulier bar for slow heel operation which is driven in the conventional manner by means of the connecting rod 1, which 55 is linked to a coulier lever. The bar 2 slides between the guide bearings 2'. The reciprocating motion of the bar 2 as the same is driven by the connecting rod 1 and slides back and forth between the guide bearings 2' is transmitted to the lever 4 by means of the pin 3 and block 3'. The 60 pin 3 and block 3' form a pivot joint and the block 3' may slide axially along the lever 4 in the tracks formed by the longitudinal ribs 4'. The lever 4 is pivotally mounted at its lower end for pivoting about a pivot joint formed by the pin 5. The pin 5 is supported by the lugs 6' rigidly connected to the internally threaded sleeves 6. The internally threaded sleeves 6 surround and are in threaded engagement with the threaded spindles 7, 7', which are 65 rotatably supported in a bracket 16, which is fastened to the knitting machine frame 15.

70 Upon the synchronous rotation of the spindles 7, 7', the sleeves 6, together with their lugs 6', are simultaneously displaced axially along the length of the spindles 7, 7' so

that the pivot point of the lever 4 at 5 is displaced in a direction substantially normal to the axis of motion of the bar 2.

At the opposite end of the lever 4 another pivot joint consisting of the pin 8 and block 8' is positioned. The block 8' slides in the track guide 9' on the driving slide 9 for the friction rod 14 which carries the friction box 11.

Upon the rotation of the spindle 7, so that the sleeves 6 are screwed to their upper end, the arm between the points 5 and 3 of the lever 4 is shortened, as shown in Fig. 2, while the lever arm between the points 3 to 8 is correspondingly lengthened. With the frequency and amplitude of the reciprocating drive bar or coulier bar 2 remaining constant, as the length of the lever arm 8-3 increases and the lever arm 3-5 decreases from the position shown in Fig. 1 to the position shown in Fig. 2, the arc of travel described by the point 8 is correspondingly increased along with the path of travel of its connected parts 8', 9, 9', and 14. Thus, as the spindles 7, 7' are rotated to move the sleeves 6 from the position shown in Fig. 1 to the position shown in Fig. 2, the path of travel of the friction rod 14 is correspondingly increased. Conversely, as the threaded spindles 7, 7' are rotated in the opposite direction and the sleeves 6 are displaced in the direction along the direction of the spindles 7, 7' from Fig. 2 to Fig. 1, the path of travel of the friction rod 14 is correspondingly reduced.

A suitable rotation of the spindles 7 is possible to displace and secure the pivot point 5 of the lever 4 at any desired point within the two limit positions as shown in Figs. 1 and 2, respectively, whereby the friction rod may always be displaced with a speed which corresponds to the reduced or increased width of the material being knit at the reinforcement portions of the stocking.

In the embodiment as shown in Fig. 4, the threaded spindles for regulating the point of the pivot point 5 are combined into a single spindle mounted parallel to the axes of motion of the bar 2 and friction rod 14. The spindle is divided into two oppositely threaded portions 27 and 27', respectively.

The pin 5 of the pivot point of the lever 4 is connected to the sleeves 26, which correspond to the sleeves 6 in Figs. 1-3 by means of the levers 24, each of which is pivotally connected to the lever 4 at 5 and the spindles 26. By rotating the spindle, the sleeves 26 are either screwed towards each other or away from each other, depending upon the direction of rotation, thus displacing the pivot point 5 closer or further away from the bar 2 along the axis of motion substantially normal to the axis of motion of the bar 2.

The embodiments as shown may, of course, have various mechanical modifications. Thus, for example, instead of having the spindles 7 and 7' as shown in Figs. 1-3, as threaded spindles, one of the spindles may be in the form of a smooth guide rod with the sleeve 6 which surrounds it in the form of a smooth guide sleeve instead of being internally threaded. In place of the blocks 3', 8', which move in the tracks, guide slots may be provided with pins 3 and 8 extending therethrough as guide pins.

The control of the spindle 7, 7' or 27, 27', and thus of the position of the sleeves 6 or 26 therewith may be effected automatically in a manner known per se. Thus, for example, the rotation of the spindles, and thus the setting of the pivot point 5 may be effected automatically by the yarn carrier narrowing device, as, for example, the device which sets the position of the stops for the friction box. In this manner, the previously required cumbersome and time-consuming adjustment of the block and the driving slide is avoided and a finely graduated change of speed of the friction rod in the intermediate range of the width of goods is made possible while avoiding any violent striking of the friction rod in its limit position.

While the invention has been described in detail with reference to the specific embodiments shown, various

changes and modifications will become apparent to the artisan which fall within the spirit of the invention and scope of the appended claims.

We claim:

- 5 1. In a flat knitting machine having a reciprocating member for driving the friction rod in slow heel operation, the reciprocating member and the friction rod being movable along substantially parallel spaced-apart axes, the improvement for controlling the stroke of the friction rod, which comprises a lever extending substantially normal to said axes pivotally connected at one end portion to a pivot, at the other end portion to the friction rod, and at the intermediate portion to said reciprocating member, the pivotal connection between said lever and one of said reciprocating members and friction rod being slidably axially along said lever, the pivotal connection between the other of said reciprocating members and friction rod being slidably axially with said lever, and means for adjustably moving said pivot substantially normal to the axes of motion of said friction rod and reciprocating member.
- 10 2. In a flat knitting machine having a reciprocating bar for driving the friction rod in slow wheel operation, the bar and friction rod being movable along substantially parallel, spaced-apart axes, the improvement for controlling the stroke of the friction rod, which comprises at least one threaded spindle rotatably secured to the knitting machine frame, an internally threaded sleeve member surrounding said spindle in threaded engagement therewith, a first pivot joint, means connecting said first pivot joint to said sleeve for moving said first pivot joint along an axis substantially normal to the axes of movement of said bar and friction rod upon movement of the said sleeve member along said threaded spindle, a lever pivotally connected at one end portion to said first pivot joint, a second pivot joint connected to the other end portion of said lever, slide joint means connecting said second pivot joint to said friction rod for sliding movement in a direction substantially normal to the axis of motion of said friction rod, a third pivot joint connected to said bar and in sliding engagement with said lever along the intermediate portion thereof.
- 15 3. Improvement according to claim 2, in which said threaded spindle is positioned with its axis substantially normal to the axes of motion of said bar and friction rod, and in which said first pivot joint is rigidly connected to said sleeve member.
- 20 4. Improvement according to claim 3, including a second substantially parallel spindle positioned on the opposite side of said first pivot joint, and a second sleeve member surrounding said second spindle and rigidly connected to said first pivot joint.
- 25 5. Improvement according to claim 4, in which said second spindle is a threaded spindle, and in which said second sleeve member is an internally threaded sleeve member in threaded engagement therewith.
- 30 6. Improvement according to claim 4, in which said second spindle and said second sleeve member define smooth bearing surfaces in sliding contact with each other.
- 35 7. Improvement according to claim 2, in which said threaded spindle is positioned with its axis substantially parallel to the axes of motion of said bar and friction rod, and in which said threaded spindle defines a second oppositely threaded portion along its length, a second internally threaded sleeve surrounding said spindle in threaded engagement with said second threaded portion, and in which said means connecting said first pivot joint to said sleeve comprises a pair of levers pivotally connected to said sleeves and said pivot joint.
- 40 8. Improvement according to claim 2, in which said threaded spindle is positioned with its axis substantially normal to the axes of motion of said bar and friction rod, and in which said threaded spindle defines a second oppositely threaded portion along its length, a second internally threaded sleeve surrounding said spindle in threaded engagement with said second threaded portion, and in which said means connecting said first pivot joint to said sleeve comprises a pair of levers pivotally connected to said sleeves and said pivot joint.
- 45 9. Improvement according to claim 2, in which said threaded spindle is positioned with its axis substantially normal to the axes of motion of said bar and friction rod, and in which said threaded spindle defines a second oppositely threaded portion along its length, a second internally threaded sleeve surrounding said spindle in threaded engagement with said second threaded portion, and in which said means connecting said first pivot joint to said sleeve comprises a pair of levers pivotally connected to said sleeves and said pivot joint.
- 50 10. Improvement according to claim 2, in which said threaded spindle is positioned with its axis substantially normal to the axes of motion of said bar and friction rod, and in which said threaded spindle defines a second oppositely threaded portion along its length, a second internally threaded sleeve surrounding said spindle in threaded engagement with said second threaded portion, and in which said means connecting said first pivot joint to said sleeve comprises a pair of levers pivotally connected to said sleeves and said pivot joint.
- 55 11. Improvement according to claim 2, in which said threaded spindle is positioned with its axis substantially normal to the axes of motion of said bar and friction rod, and in which said threaded spindle defines a second oppositely threaded portion along its length, a second internally threaded sleeve surrounding said spindle in threaded engagement with said second threaded portion, and in which said means connecting said first pivot joint to said sleeve comprises a pair of levers pivotally connected to said sleeves and said pivot joint.
- 60 12. Improvement according to claim 2, in which said threaded spindle is positioned with its axis substantially normal to the axes of motion of said bar and friction rod, and in which said threaded spindle defines a second oppositely threaded portion along its length, a second internally threaded sleeve surrounding said spindle in threaded engagement with said second threaded portion, and in which said means connecting said first pivot joint to said sleeve comprises a pair of levers pivotally connected to said sleeves and said pivot joint.
- 65 13. Improvement according to claim 2, in which said threaded spindle is positioned with its axis substantially normal to the axes of motion of said bar and friction rod, and in which said threaded spindle defines a second oppositely threaded portion along its length, a second internally threaded sleeve surrounding said spindle in threaded engagement with said second threaded portion, and in which said means connecting said first pivot joint to said sleeve comprises a pair of levers pivotally connected to said sleeves and said pivot joint.
- 70 14. Improvement according to claim 2, in which said threaded spindle is positioned with its axis substantially normal to the axes of motion of said bar and friction rod, and in which said threaded spindle defines a second oppositely threaded portion along its length, a second internally threaded sleeve surrounding said spindle in threaded engagement with said second threaded portion, and in which said means connecting said first pivot joint to said sleeve comprises a pair of levers pivotally connected to said sleeves and said pivot joint.
